CLAIM

The ornamental design for a puzzle case, as shown and described.

DESCRIPTION

FIG. 1 is a top, front, left side perspective view of the puzzle case in accordance with my design showing four components in an assembled state;

FIG. 2 is a top, front left perspective view of the puzzle case in an exploded view;

FIG. 3 is a side elevation view of the puzzle case in an assembled state;

FIG. 4 is a top, front, left side perspective view of the first component of the puzzle case;

FIG. 5 is a top, front, left side perspective view of the second component of the puzzle case;

FIG. 6 is a top, front, left side, perspective view of third component of the puzzle case; and,

FIG. 7 is a top plan view of the fourth component of the puzzle case.

The bottom, rear, right side views form no part of the claimed design.

The broken lines show portions of the puzzle case that form no part of the claimed design.
